ATTORNEY

UNITED STATES PATENT OFFICE.

ARTHUR W. WADSWORTH, OF FORT THOMAS, KENTUCKY, ASSIGNOR TO THE WADSWORTH WATCH CASE COMPANY, OF DAYTON, KENTUCKY, A CORPORATION OF KENTUCKY.

DUSTPROOF GUARD.

Application filed March 12, 1925. Serial No. 14,947.

My invention relates to means for preventing dust and dirt from getting into the opening around the stem of a two-piece watchcase.

5 The objects of my invention are to provide a simple, efficient, serviceable and economical guard and means for holding it in a two-piece watchcase for the purpose of preventing dirt, dust, and the like from getting into the watchcase through the usual opening around the winding stem in the watchcase.

10 My invention consists in providing a hollow guard having members thereon engaging the inside and outside of the walls of the watchcase, whereby said guard is held in position by said walls when the watchcase is closed or the parts thereof are put together.

15 My invention also consists in the parts and in the construction, combination, location and arrangement of parts, as herein set forth and claimed.

In the drawing:

20 Fig. 1 shows my dust-proof tube and crown in central vertical section and the relation of the tube with the two-piece watchcase, the latter shown partly in section and partly by dotted lines;

25 Fig. 2 is a vertical section of the crown before receiving the tube, the dotted lines indicating the part burnished over after the tube has been received;

30 Fig. 3 is a vertical section of the dust-proof tube;

35 Fig. 4 is an enlarged vertical section similar to Fig. 1 but showing the crown and stem in the pulled out or setting position;

40 Fig. 5 is a perspective view of the crown dust-proof tube and stem, the first two parts being shown in vertical section; and

45 Fig. 6 is an isometric view of the dust-proof tube.

Heretofore in the manufacture of two-piece watchcases it has been the practice to provide a hole through the two adjacent parts of the watchcase to receive the winding and setting stem. This hole was somewhat larger in cross section than the stem in order to permit its insertion, thus leaving considerable space around the stem through which dirt, dust and the like was readily admitted, thereby subjecting the movements to damage therefrom.

In the embodiment of my invention, as illustrated and which shows a preferred con-

struction, I overcome this objectional feature by providing a dust-proof guard 1 comprising a short tube or sleeve which is received in hole 2 in a two-piece watchcase 3 of the usual construction. This tube is provided with spaced apart outwardly extending annular flanges 4 and 4' at one end to form annular groove 5 which receives the adjacent abutting edges of the back 6 and front or bezel 7 of the watchcase between said annular flanges adjacent to said hole, thereby forming a close dust-proof connection of said guard with said back and bezel and at the same time permitting lateral movement or play of said guard relative to the back and bezel for the purpose of permitting the stem to adapt itself to any variation in the location of the parts of the movement to which said stem is connected. The other end of said guard is provided with an inturned flange 8.

55 The crown 9 comprises a knurled knob and serves as convenient means to pull the stem outwardly for setting the watch or for turning it in winding. The crown is provided with a deep annular channel 11 to receive the inwardly flanged end of the guard and this channel is extended laterally adjacent the surface to provide an annular recess 12 to partly receive flange 4' of the guard to effect a more compact and close fit of the parts. The crown is also provided with central stud or boss 13 having an internally threaded socket 14 into which the winding and setting stem 10 is screwed and held. There is also slight play between the inturned flange 8 and boss 13 to permit the stem to be readily pulled outwardly for setting the watch, as shown in Fig. 4.

60 In assembling the parts boss 13 is inserted through the inturned flanged end of the guard and the free end of the boss is then burnished to form an annular rim 15 to prevent the unintentional detachment of the crown even though the inner end of the stem should become disconnected from the works or watch movement. The stem 10 is then screwed into position into socket 14. The back 6 and bezel 7 are then snapped together and into annular groove 5 between the flanges 4 and 4' adjacent stem-hole 2. The parts are thus held in position relative to each other and the crown is adapted to be pulled outwardly relative to the guard which

at all times maintains its dust-proof relation with the crown and with the back and bezel, thus efficiently serving to exclude dust, dirt and the like under all conditions and position of the parts relative to each other.

It is thus seen that I have produced a very simple, yet efficient and economical dust-proof construction for a two-piece watch-case.

10 While I have shown a particular construction, it is understood that my invention is capable of modification without departure from its scope or spirit, as defined in the claims.

15 I claim:

1. In dust-proof guards for a two-piece watchcase having a stem-hole in one edge, a crown having a boss with an annular channel therearound, a tubular guard having an 20 inturned flange at one end adapted to be slidably secured on said boss, a stem secured to said boss, said guard having on its other end spaced apart flanges forming an annular groove adapted to receive the adjacent 25 edges of the back and bezel, respectively, surrounding said stem-hole whereby a dust-proof connection is formed between said guard and crown and between said guard and said back and bezel.

30 2. In a dust-proof guard for a two-piece watchcase having a stem-hole, a crown having a boss with an annular channel there-around and an annular recess adjacent said annular channel, a tubular guard having an inwardly flanged end adapted to closely fit and be slidably mounted on said boss, means 35 on said boss to hold said crown in operative relation with said guard, said guard having spaced apart flanges forming a groove 40 adapted to receive the adjacent edges of the

back and bezel surrounding said hole whereby a close fit is obtained between said case and guard and whereby one of said flanges is adapted to fit in said annular recess to provide compactness.

3. In a dust-proof guard for a two-piece watchcase having a stem-hole, a tubular guard detachably mounted in said hole and forming a close connection with said case, and a crown slidably mounted on said guard 50 and forming a close connection therewith.

4. A guard for a watchcase comprising a tube or sleeve having outwardly extending spaced apart flanges forming a groove at one end and having an inturned flange at the 55 other end, for the purposes specified.

5. In a dust-proof guard, a crown having a boss, a tubular flanged guard in which said boss is slidably mounted, and means for preventing detachment of said crown from said 60 guard.

6. In a dust-proof guard for a two-piece watchcase, a crown having an internally threaded boss with an annular channel there-around, a tubular guard having an inturned 65 flange closely fitting said boss which is slid-able therein, and a rim formed on said boss whereby it is held from disengagement from said guard, a stem screwed in said boss, and means for mounting said guard upon a 70 watchcase.

7. A guard for a two-piece watchcase comprising a tubular member having spaced apart flanges thereon forming a groove adapted to receive the adjacent edges of the 75 back and bezel of said watchcase whereby it is held in position and forms an efficient dust guard.

ARTHUR W. WADSWORTH.
